WHEEL COVER

Clarence D. Zierhut, Granada Hills, Calif., assignor to Shore-Calnevar, Inc., Paramount, Calif., a corporation of California

Filed Apr. 17, 1961, Ser. No. 64,790

Term of patent 14 years

(Cl. D14—30)

FIG. 1 is a front elevational view of a wheel cover showing my new design;

FIG. 2 is a side elevational view of the wheel cover shown in FIG. 1;

FIG. 3 is a top plan view of the wheel cover shown in FIG. 1;

FIG. 4 is a bottom plan view of the wheel cover shown in FIG. 1; and

FIG. 5 is a sectional view taken on the line 5—5 of FIG. 1.

The dominant features of my design reside in the portions shown in full lines.

I claim:

The ornamental design for a wheel cover, substantially as shown and described.
